UNITED STATES PATENT OFFICE

ALVA O. WRIGHT, OF NORTH SALEM, INDIANA

DISPENSING RECEPTACLE

Application filed October 31, 1925. Serial No. 66,025.

My invention relates to new and useful improvements in receptacles and more particularly to a receptacle for dispensing liquids such as oils, the principal object of the invention residing in the provision of such a device into which the oil or other liquid may be introduced or from which it may be dispensed without removing the closure cap, the closure cap carrying a spout of such a size that the oil or other liquid may be introduced therethrough or through which it may be dispensed into the crank case filling opening of an engine or other suitable place.

Another object of the invention resides in the provision of means for discharging air from the receptacle as the same is being filled and allowing air to enter the receptacle when dispensing therefrom.

A further object of the invention resides in the provision of a novel form of closure cap having a spout and handle formed on or secured thereto, said spout and handle adapted to be removed with the closure cap as a unit and means being provided whereby the closure cap and its associated parts may be securely connected to a glass jar or other form of receptacle so that the entire device may be positioned upon a shelf or other suitable support when not in use but may be readily carried from place to place for dispensing the contents therefrom.

With the above and other objects in view, which will appear as the description proceeds, my invention consists in the novel form of construction and arrangement of parts described in the following specification and illustrated in the accompanying drawings, and while I have illustrated and described the preferred embodiments of the invention, as they now appear to me, it will be understood that such changes may be made as will fall within the scope of the appended claims.

In the drawings:—

Fig. 1 is a side elevation with parts shown in vertical section.

Fig. 2 is a bottom plan.

Fig. 3 is a bottom plan of the closure cap removed from the receptacle.

Fig. 4 is a side elevation illustrating a slightly different form of the invention.

Fig. 5 is a bottom plan, with parts shown in horizontal section of the construction shown in Fig. 4, and

Fig. 6 is a side elevation of a further modified form of the invention with parts shown in section.

My receptacle is primarily intended for holding and dispensing oils such as are used in the crank case of internal combustion engines and is of such a size as to hold a predetermined quantity and so constructed as to provide a spout which may be introduced into the filling opening of the crank case. The usual practice in dispensing oils at an automobile "service station" or like place has been to draw the desired amount of the oil or other liquid into a measuring cup or the like and then to pour the same into the crank case filling opening. The question of time enters into the dispensing of oils as the customer desires to secure the quickest possible service and the employee's time is of considerable value to the employer. My receptacle, as has been previously stated, is of a size to hold a predetermined quantity of the oil or similar fluid and a number of the receptacles may be stored upon a shelf or similar support and when a customer desires oil or the like it is only necessary for the employee to pick up one of the receptacles and dispense the oil into the crank case it being seen that the usual time for filling the receptacle from the ordinary oil pump is eliminated. These receptacles may be filled at the leisure of the employee and the spout thereof is of such a size that the oil or other fluid may be discharged therethrough into the receptacle.

In the drawings the numeral 1 indicates a glass jar or other suitable receptacle adapted to contain the desired quantity of the oil or the like, either a quart, a pint, or other amount, in the instance shown the receptacle 1 being in the form of what is known as the ordinary "Mason fruit jar" having the threaded neck 2 to receive the metal threaded cap 3. Formed on or secured to the cap 3 is the spout 4, said spout preferably extending through an opening formed in the cap, as more particularly illustrated in Fig. 1, 100

with its inner end flanged as shown at 5. The outer end of the spout is cut at an angle as shown at 6 to aid in dispensing the oil or other liquid. Secured to the spout and cap 5 is the hollow handle 7 of the shape shown, an opening 8 being formed in the cap 3 and communicating with the hollow handle 7, adjacent its upper end, and an opening 9 is formed in and communicates with the hollow handle adjacent its lower end.

Secured to the lower end of the handle is the metal band 10 of a diameter to encircle the receptacle 1 with the space 11 between the ends, a coiled spring 12 being connected 15 to the ends of the band for drawing the band tightly around the receptacle.

Received in the cap 3 is a disc or washer 13 this disc or washer having an opening 14 adapted to register with the opening through 20 the spout 4 and the opening 15 adapted to register with the opening 8 in the cap.

As can be readily appreciated the cap 3 may be easily secured to the glass receptacle 1 and supports the handle 7 at the upper end, 25 the lower end of the handle being connected to the receptacle by means of the band 10. The spout 4 is of such a diameter that the oil or other liquid may be discharged therethrough from an oil pump or the like and 30 as the oil is supplied to the receptacle the air from the receptacle will pass through the opening 15 in the disc or washer 13, the opening 8 in the cap 3, the hollow handle 7, and out through the opening 9. When dispensing 35 the oil or other fluid from the receptacle air may enter in a reverse direction.

In Figs. 4 and 5 of the drawings I have shown a slightly different form of the invention in which the handle secured to the cap 40 3 is shown at 16 and extends parallel with the outer surface of the receptacle 1 and has the open end shown at 17. In this form of the invention the opening 8 in the cap communicates with the handle 16 and the air passing 45 from the receptacle or into the receptacle discharges or enters through the open end 17. In the form of the invention shown in Figs. 4 and 5 a band 18 encircles the receptacle 1 and is bent to form the arms 19 and 20, the 50 arm 20 being extended around the handle and parallel with the arm 19 at the point 21. Secured between the arms 19 and 20 is a block 22, preferably of rubber, the end of this block engaging the receptacle 1 as shown 55 more particularly in Fig. 5. A bolt 23 passes through the arms 19, 20 and 21 as well as the block 22 and receives the nut 24 as shown. With the construction disclosed in Figs. 4 and 60 5 the band 18 may be adjusted vertically by movement upon the handle, it being understood that there is sufficient space between the inner end of the block 22 and the end of the arm 20 to allow for movement upon the handle 16 for the adjustment. In this 65 form of the invention the oil or other liquid

may be introduced or discharged from the receptacle in the same manner as previously described, the air from the receptacle when filling passing through the opening 8 in the cap and then through the handle 16 for discharge through the end 17. When dispensing from the receptacle the air will enter the open end 17 pass through the handle 16 and through the opening 8 in the cap into the receptacle.

In Fig. 6 I have illustrated a further modified form of the invention in which a receptacle of glass is shown at 25 and has the integral glass spout 26 and integral glass handle 27. An opening 28 is formed in the upper end of the handle for the passage of air. Gauge marks are shown at 29 and 30 so that the desired quantity of the fluid may be noted. In this form of the invention the air passes through the opening 28 and it will be understood that the spout 26 will be of such a size that the oil or other liquid may be introduced therethrough from the oil pump or other suitable receptacle.

Having fully described my invention what I claim as new and desire to secure by Letters Patent is:

1. An attachment of the character described adapted to be detachably connected to a receptacle, said attachment including a cap, a spout carried by the cap and of a size whereby the receptacle may be filled therethrough, a hollow handle carried by the cap and adapted to extend parallel with the receptacle, an opening being formed in the cap and communicating with the hollow handle whereby air may be discharged from the receptacle or introduced thereto, and a band connected to and vertically adjustable relative to the handle for connecting the handle to the receptacle.

2. An oil can comprising a container body, a cap screwed thereon, a spout carried by the cap, an air pipe carried by the cap and having an end portion adapted to extend along the body of the container and spaced therefrom and a strap member securing the free end portion of the pipe to the container body.

3. An oil can comprising a container body, a cap screwed thereon, a spout carried by the cap, an air pipe carried by the cap and communicating therewith and having an end portion extending along the body of the container and spaced therefrom, a strap member passing around the body and passing around the free end portion of the pipe and having overlapping ends and means for drawing the strap member tightly around the container body and the pipe and adapted to hold the cover against rotary movement with relation to the container body.

In testimony whereof I hereunto affix my signature.
